US0D1047398S

(12) **United States Design Patent** (10) **Patent No.:** **US D1,047,398 S**
(45) **Date of Patent:** **** Oct. 22, 2024**

(54) **INSOLE**

(71) Applicants: **Zhuangli Qin**, Xiaogan (CN);
Zhengjun Lv, Yichang (CN)

(72) Inventors: **Zhuangli Qin**, Xiaogan (CN);
Zhengjun Lv, Yichang (CN)

(**) Term: **15 Years**

(21) Appl. No.: **35/519,842**

(22) Filed: **Dec. 21, 2023**

(80) **Hague Agreement Data**

Int. Filing Date: **Dec. 21, 2023**

Int. Reg. No.: **DM/234542**

Int. Reg. Date: **Dec. 21, 2023**

Int. Reg. Pub. Date: **Jan. 26, 2024**

(51) **LOC (14) Cl.** **02-04**

(52) **U.S. Cl.**

USPC **D2/961**

(58) **Field of Classification Search**

USPC D2/961, 915, 947, 951, 953, 954, 955,
D2/957, 958, 959; D24/192

CPC A43B 17/00; A43B 17/08; A43B 17/10;
A43B 17/002; A43B 17/023; A43B
17/026; A43B 17/105; A43B 17/107;
A43B 17/003; A43B 17/006
